ADJUSTABLE LOUVER TYPE VENTILATOR

Lester L. Smith, Peoria, Ill.

Application July 30, 1952, Serial No. 301,688

3 Claims. (Cl. 160—223)

This invention relates to adjustable louver type ventilator structures and has particular adaptation to such structures which are adjustable at installation to fit gables and the like having various pitch angles.

The structure disclosed herein is a simplified and modified form of the adjustable louver type ventilator disclosed in my copending application Serial No. 173,182, filed July 11, 1950, and entitled Adjustable Louver Type Ventilator.

One of the general objects of this invention is to provide a louver type ventilator structure adapted to placement at the gable of a building and which is not only adjustable to fit various roof pitch angles, but which maintains relatively uniform spacing between the louver slats when adjusted to the various angles.

A further object is the provision of an adjustable ventilator of the louver type from which angularly disposed side frames and the like have been omitted without losing the unitary nature of the structure and the ability to effect quick adjustment for a relatively wide variation of angle. In the disclosed structure, the ends of the louvers stay connected to one another without the use of the side frames, and are suitably shaped so as to be adapted to be secured directly to the gable or other structure that is to be ventilated. The ends of the louvers, by being connected for linear movement relative to one another, provide angularly related sides on the ventilator, and can be directly attached to the structure to be ventilated without the use of separate side frames.

Other objects and advantages of the invention will be apparent from the following description and the accompanying drawings, in which similar characters of reference indicate similar parts throughout the several views.

Referring to the two sheets of drawings:

Fig. 1 is a front elevational view showing the adaptation of a preferred embodiment of my adjustable louver type ventilator to the gable of a building which is depicted fragmentarily.

Fig. 2 is a fragmentary front elevational view of a portion of the ventilator shown in Fig. 1, drawn to a larger scale than Fig. 1 and showing more details of the louver structure;

Fig. 3 is a fragmentary rear elevational view of a portion of the louver structure shown in Figs. 1 and 2;

Fig. 4 is a fragmentary perspective view, partly in section, showing the various parts of an individual louver, and the mode of attachment of the louver to a central spacing member;

Fig. 5 is a sectional view taken substantially on a line 5—5 of Fig. 2, and in the direction of the arrows;

Fig. 6 is a sectional view taken substantially on a line 6—6 of Fig. 2 and in the direction of the arrows;

Fig. 7 is an enlarged sectional view taken substantially on a line 7—7 of Fig. 2 and in the direction of the arrows;

Fig. 8 is an enlarged sectional view taken substantially on a line 8—8 of Fig. 2, and in the direction of the arrows.

It is definitely desirable that a ventilator for a gable or the like should be adjustable angularly, so as to be capable of fitting the various angles of different gables. Heretofore such adjustability has been effected with the aid of side frame members that are a part of the louver structure and that are angularly adjustable to positions corresponding to that of the particular gable to which the ventilator is to be attached. With the disclosed structure, the side frames are omitted, and the ends of the

2

louvers collectively define the sides of the ventilator which are attached to the gable and are adjusted with respect to one another collectively to define an angle corresponding to that of a roof.

5 With reference to the drawing wherein a preferred embodiment of the invention is depicted for illustrative purposes, Fig. 1 shows the adaptation of an adjustable louver type ventilator 10 to the gable portion of a building 11, wherein the ventilator is secured in practically flush relation to siding boards 12 at the apex of a pitch roof 13, and wherein the ventilator is adjustable to fit snugly into the angle formed between gable trim strips 14.

Giving further general consideration to the structure of my preferred ventilator structure, it includes a top 15 louver plate 15 which lies at the apex of the ventilator and provides a vertex to the general triangular shape to which the general configuration of the disclosed ventilator complies. Below the top louver plate 15, a series of extensible louver slats 16 are provided, which louver slats extend in substantially parallel relationship to one another and are spaced from one another at their mid-portions to provide ventilating air passages 17, as shown in Figs. 5 and 6. The mid-portions of the slats 16 are shaped to be inclined outwardly, as also shown in Figs. 5 and 6. A bottom extensible louver slat 18 extends across the bottom of the series of slats 16 and is substantially flat and vertical, thus providing a substantially flat bottom flange portion for the ventilator assembly.

Considering my illustrated ventilator in greater detail, 30 and since it is one of the purposes of my invention to provide a ventilator structure in which substantially uniform spacing is maintained between adjacent louver slats, regardless of the degree to which the slats are longitudinally extended or contracted, I have provided a spacer 35 rail 19 which, in the embodiment shown, constitutes a channel. The upper end of the spacer rail 19 is secured to the louver plate 15 by fastening means, such as rivets 20. The spacer rail is also secured to stationary mid-parts 21 of the louver slats 16 by fastening means, such as rivets 22, and to a stationary mid-part 23 of the bottom slat 18 by fastening means such as rivets 24.

Each of the louver slats 16, in addition to the stationary mid-part 21, has movable end parts 25 telescopically engaged with the opposite ends of the stationary mid-part 21 in opposed relationship to one another and longitudinally slidable relative to the stationary mid-part; while the bottom louver slat 18 likewise has movable end parts 26 in opposed relationship at the opposite ends of the stationary mid-part 23, and telescopically engaged 50 with the latter part for longitudinal sliding movements. In my disclosed structure, the telescopic engagement of the stationary mid-parts with the movable end parts of the louvers is accomplished by having complementary sectional shapes for the engaged portions of the louver parts and by providing return bent flanges 27 along the opposed longitudinal edges of the stationary mid-parts 21 which overlie and slidably receive the opposite margins of the movable end parts 25 at the opposite ends of the stationary mid-parts. Similarly, the opposed longitudinal edges of the stationary mid-part 23 of the bottom slat 26 have return bent flanges 28 which overlie and slidably receive the opposite margins of the movable end parts 26. These margins are provided with return bent flanges 29 which stiffen the end parts 26. The sides 55 of the spacer member 19 are folded into return bent flanges at the lower end of the spacer member so that they can fit into the lower return bent flange 28 on the mid-part 23 of the bottom slat 18, as shown in Figs. 3 and 5.

In each instance, the outer extremities of the movable end parts 25 and 26 of the louver slats are substantially flat and overlap one another. The extensible louver slats increase sequentially in length from the top louver plate 15 toward the bottom. The successive increases in the lengths of the louver slats are generally uniform, so as to provide uniform slopes to the opposite ends of the assembly. In the disclosed structure, the stationary mid-parts 21, as well as the end parts of the slats, are successively longer from the top louver plate 15 toward the bottom.

As shown in Fig. 4, each movable end part of each

louver slat 16 has a longitudinally extending slot 30 adjacent one side edge 31 thereof, and somewhat spaced from an end 32 of the slat, and also has an opening 33 which is farther from the side margin 31 and nearer the end margin than the slot 30. The opening 33 in the end part 25 of each louver slat 16 receives or mounts a headed member such as a rivet 34 which extends through the slot 30 in the corresponding end part 25 of the adjacent and next longer louver slat 16. The rivet 34 and a washer 35 mounted on the rivet hold the end parts of successive slats 16 together, as shown in Figs. 2, 3 and 7. The rivet and the slot 30 permit the end parts of successive slats 16 to have relative movement longitudinally of the slats when the louver assembly is adjusted to fit the angle of a gable to which the louver assembly is to be applied. The washer 35 has a diameter larger than the width of the slot 20 and the diameter of a spread header 36 on the rivet 34. The washer may be dished, as indicated in Fig. 7, so as to present a convex face toward the slot 30 and a concave face toward the rivet head 36. The slots 30 in the top or smallest extensible louver slat 16 receive rivets or headed members 34 which are mounted in the louver plate 15. The openings 33 in the bottom or largest louver slat 16 mount headed members 34 which are received in longitudinally extending slots 30 in the end parts 26 of the bottom slat 18.

The side edge 31 and end 32 of each end part of the slats 16 and 18 meet in generally right angular relationship and define an attaching tab 37 through which fastening means, such as a nail 38, may be applied to secure the end part to a gable of a building, as shown in Fig. 1. The headed members 34 and associated washers 35 hold adjacent louver end parts 25 and 26 together in individually and linearly adjustable relationship, so that collectively they can be set to fit various pitch angles of gables or the like.

The headed members 34 and the slots 30 which receive them cooperate with the spacer member 19 in holding constant the transverse spacing of the louver slats from one another, regardless of the adjustment of the movable end parts 25 and 26 of the louvers.

From the foregoing description, and by reference to the accompanying drawings, it may be readily understood that I have provided a louver assembly which is constructed and arranged for quick and easy adjustment to various pitch angles within a range, without changing the spacing between adjacent louver slats, so as to alter the ventilation provided. Furthermore, the structure is adapted to rapid production and economy of material. While I have illustrated a preferred embodiment of

my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States is:

- 10 1. In an adjustable louver type ventilator of generally triangular shape, the combination comprising a series of longitudinally extensible louver slats arranged in spaced and parallel relationship, which louver slats are of progressively increasing length from one louver slat to the next across the series, the louver slats of the series including intermediate parts and end parts slidably lengthwise of the intermediate parts, a spacer member extending across the intermediate parts and secured thereto so as to hold constant the spacing of the louver slats in a direction transverse of their lengths, said end parts having longitudinally extending slots therein and headed members near the outer ends thereof, the headed member on the end part of each louver slat projecting through the slot on the end part of the next adjacent louver slat and holding the end parts of the said given louver slat against the end parts of the said adjacent louver slat while being movable in the slot to provide for lengthwise movements of the end part of the said given louver slat with respect to the end part of the said adjacent louver slat.
- 15 2. In an adjustable type ventilator of generally triangular shape, the combination specified in claim 1, and further comprising a plurality of washers, each washer being mounted on a headed member between the end of the headed member and the end part having the slot through which the headed member projects, and said washer having a diameter larger than the head and the width of said slot.
- 20 3. In an adjustable type ventilator of generally triangular shape, the combination specified in claim 2, and wherein the washers are concavely dished and are placed on the headed members so as to have their concave sides facing toward the ends of the headed members which carry the washers and their convex sides facing toward the slots in which the headed members are located.
